PROCESS AND APPARATUS FOR THE CONVERSION OF HYDROCARBON LIQUIDS AND GASES

Malcolm P. Youker, Bartlesville, Okla., assignor to Phillips Petroleum Company, Bartlesville, Okla., a corporation of Delaware

Application June 18, 1931, Serial No. 545,309

5 Claims. (Cl. 196—116)

This present invention is a continuation in part of and improvement in a Process for the conversion of hydrocarbon gases which was originally disclosed in application for patent by 5 Malcolm P. Youker, filed in the United States Patent Office May 1, 1925, under United States Patent Office Serial No. 27,234 now United States Patent 1,800,586.

In converting hydrocarbon gases to hydrocarbon liquids by means of heating such gases in the presence of fuel oil or gas oil, as disclosed in said patent application, I have found that the apparatus has a tendency to coke up rather rapidly. In this application for patent I will disclose a particular method by which a mixture of hydrocarbon gases and heavy hydrocarbon oil or any hydrocarbon material may be continuously heated and converted while at the same time a minimum amount of carbon will be deposited 20 in the apparatus. An object of my invention is to provide a process by which either gaseous or liquid hydrocarbon materials may be converted to new hydrocarbon compounds without the production of excessive quantities of free carbon. This 25 object and other objects which will be made apparent in the following specification are accomplished by my new process.

My new process will be understood from the following specification taken in connection with 30 the attached drawing on which a form of apparatus by which my new process may be carried out is illustrated in side elevation.

Referring to the drawing, the numeral 1 designates a furnace or first passageway in the bottom of which is mounted a gas burner 2. Any suitable means of firing the bottom of this furnace may be utilized, the gas burner being shown hereon for purposes of illustration. The numeral 3 designates an unfired chamber or second passageway. The numeral 4 designates a smoke stack. A breeching 5 leads from the top of the furnace 1 into the smoke stack 4. A breeching 6 leads from breeching 5 into the top of unfired chamber 3. A damper 7 is mounted in breeching 45 5 at a point between smoke stack 4 and breeching 6 and may be operated to restrict the flow of gases through breeching 5 into smoke stack 4. A breeching 8 leads from the bottom of unfired chamber 3 into the smoke stack 4. A damper 9 is mounted in breeching 8 and may be operated to control the flow of gases through unfired chamber 3 into smoke stack 4. Fuel may be fired in the bottom of furnace 1 and the gases of combustion resulting therefrom will flow upward 50 through this furnace and thence from the top of

furnace 1 through breeching 5 into smoke stack 4. By partially closing damper 7 and partially opening damper 9 a portion of the gases of combustion which flow through breeching 5 may be diverted therefrom and caused to flow through breeching 5 6 and downward through unfired chamber 3 and through breeching 8 into smoke stack 4. It is apparent that by manipulation of dampers 7 and 9 any desired percentage of the stack gases leaving furnace 1 may be caused to flow downward through unfired chamber 3. A tube 10 in which is mounted a pump 11 leads through chamber 1 in the form of a coil and is connected to a second coil 10a which is arranged in the unfired chamber 3. A valve 12 is mounted in a discharge line leading from the coil in the unfired chamber 3. A pipe 13 in which is mounted a pump 14 leads into the tube 10. Hydrocarbon liquid may be delivered through the tube 10 by means of the pump 11. Hydrocarbon gas in either liquid or gaseous state may be delivered through the tube 10 by means of the pump 14 and the pipe 13. The furnace 1 will be fired and hydrocarbon materials will be forced by pumps 11 or 14 through the coils 10 and 10a. Pressure will be maintained in the tube 10 by means of the valve 12. The burner 2 will be so regulated that hydrocarbon materials passing by way of tube 10 through furnace 1 will be heated therein to the proper temperature for conversion, which in most cases will range between 800 degrees F. and 1000 degrees F. The heated material after leaving furnace 1 will pass through that part of the coil 10a which is disposed in the unfired chamber 3 and by manipulation of the dampers 7 and 9 a portion of the gases of combustion which leave the furnace 1 will pass through the unfired chamber 3 and serve to prevent loss of heat from the coil 10a which is mounted in said unfired chamber 3. In some cases a sufficient quantity of gases of combustion will be caused to flow through unfired chamber 3 to heat the coil 10a to a limited degree. The pressure maintained in the coils will be varied to suit the particular material which is being converted. For some materials it may be found desirable to maintain a pressure in the coils as low as 300 pounds per square inch while in other cases it may be desirable to maintain a pressure in the coils as high as 3500 pounds per square inch.

In order to heat and convert hydrocarbon materials while passing through a tube, it is necessary that these materials pass through a considerable length of tube after they have been heated to a conversion temperature. It has

been customary in the past to mount in a furnace a heating tube which is sufficiently long to provide time for conversion after conversion temperature has been obtained in the tube, and this arrangement has been to some extent satisfactory; however, I have found that due to the fact that all of the gases of combustion pass over the entire tube such an arrangement is apt to cause the formation of free carbon in excessive quantities in the conversion portion of the tube and the deposition of this carbon necessitates the frequent shutting down of such equipment for cleaning purposes. I find that it is much more desirable to divide this tube into a heating portion and a conversion portion, the former portion being subjected to rapid heating while the latter portion is subjected to only very gentle heating, if any. That part of the tube 10 which is mounted in the furnace 1 is used for rapidly bringing the hydrocarbon material to conversion temperature while that part 10a of the tube which is mounted in unfired chamber 3 is provided for the purpose of retaining the materials to be converted at conversion temperature through a sufficient period of time to permit the conversion reaction to proceed to somewhere near equilibrium. The hydrocarbon material having been brought to conversion temperature in the furnace 1, conversion of the same may be obtained in unfired chamber 3, even though no heating is accomplished in unfired chamber 3, provided that this chamber is well insulated to prevent heat loss from that part 10a of the tube which is mounted therein. The provision which I have shown for passing stack gases through the unfired chamber 3 is a method by which heat loss to surrounding objects from the conversion portion 10a of the tube may be prevented and by which gentle heating of the materials undergoing conversion may be accomplished thus supplying heat for an endothermic reaction.

After the converted hydrocarbon materials pass the valve 12 they will of course be largely in a vapor phase and any of the conventional systems of fractionating columns and condensers may be utilized to separate these converted materials into various fractions and condense and cool them.

Numerous other arrangements of a similar nature could be made. While I have described in detail one arrangement of a combined heating and conversion tube, I do not wish to limit myself in my claims to this particular arrangement but wish to claim broadly all of the advantages which are inherent in my new process, the fundamental principle of which is that hydrocarbon materials which are to be converted are first heated in a tube through which such materials are caused to flow progressively and, second, these materials are caused to flow through a tube in which conversion of such materials is accomplished, the second stage being accomplished under heating conditions which are at least more gentle than those conditions which are now conventionally utilized for this purpose. While that part 10a of the tube which is mounted in the unfired chamber 3 may be of larger cross-sectional area than that part 10 of the tube which is mounted in the furnace 1, the cross-sectional area of any part of the tube will be so restricted that the materials will be caused to flow continuously through the tube so that no part of the material will lag materially behind the main body of materials flowing therethrough.

It is desirable that the length of that portion of the tube 10 which is mounted in the unfired chamber 3 shall be equal to or greater than the length of that portion of the tube 10 which is mounted in the furnace 1. For ordinary practical use, about 2,000 linear feet of 2½" inside diameter tubing may be mounted in the furnace 1 and about 3,000 linear feet of 2½" inside diameter, or 3" inside diameter, tubing may be mounted in the unfired furnace 3. Such an arrangement of tubing will be found to give excellent results. In any particular case it will be found desirable to carry out certain experiments to determine the relative length of tubing required for heating and converting. In general, higher pressures maintained in the tube 10 will reduce the necessary length of tubing used for conversion purposes and vice versa.

The apparatus disclosed herein, as well as the method, may be employed for the treatment of hydrocarbon liquid alone, hydrocarbon gases alone, or for treating mixtures of hydrocarbon liquids and gases.

I claim:

1. A hydrocarbon fluid conversion apparatus, comprising first and second chambers, communicating elongated restricted passageways extending through said chambers, means for forcing hydrocarbon fluids into the inlet of the passageway which extends through the first chamber, means for generating hot products of combustion for the first chamber, a smoke stack, a breeching leading from the first chamber to the smoke stack, a branch conduit connecting a point in the breeching to one end of the second chamber, a damper in the breeching between said point and the smoke stack, another branch conduit placing the other end of the second chamber in communication with the smoke stack, and a damper in the last mentioned branch.

2. A hydrocarbon fluid conversion apparatus, comprising first and second chambers, communicating elongated restricted passageways extending through said chambers, means for forcing hydrocarbon fluids into the inlet of the passageway which extends through the first chamber, means for generating hot products of combustion for the first chamber, a smoke stack, a breeching leading from the first chamber to the smoke stack, a branch conduit connecting a point in the breeching to one end of the second chamber, a damper in the breeching between said point and the smoke stack, another branch conduit placing the other end of the second chamber in communication with the smoke stack, and a damper in the last mentioned branch, and a pressure control valve for said passageways arranged at the outlet end of the second passageway.

3. A hydrocarbon fluid conversion apparatus, comprising first and second chambers, communicating elongated restricted passageways extending through said chambers, means for forcing hydrocarbon fluids into the inlet of the passageway which extends through the first chamber, means for generating hot products of combustion for the first chamber, a smoke stack, a breeching leading from the first chamber to the smoke stack, a branch conduit connecting a point in the breeching to one end of the second chamber, a damper in the breeching between said point and the smoke stack, another branch conduit placing the other end of the second chamber in communication with the smoke stack, and a damper in the last mentioned branch, the first passageway being about 2000 linear feet in length and of about 75

2½ inch inside diameter, and the second passageway being of greater length and of about the same diameter.

4. A process for converting hydrocarbon fluids comprising continuously passing a mixture of normally gaseous hydrocarbons and normally liquid hydrocarbons through an elongated heating coil of restricted cross sectional area extending through a first passageway, passing a stream of hot products of combustion through said passageway and past said coil for heating the mixture passing through the coil to the temperature of conversion, directly passing the mixture thus heated through a second elongated coil of restricted cross sectional area substantially entirely within a second passageway, diverting a portion of the stream of hot products of combustion after said stream has passed the entire length of coil in the first passageway, and passing the remainder of the stream of hot products of combustion through the second passageway and thereby maintaining the mixture in the second coil at the temperature of conversion.

5. A process for converting hydrocarbon fluids

comprising continuously passing a mixture of normally gaseous hydrocarbons and normally liquid hydrocarbons through an elongated heating coil of restricted cross sectional area extending through a first passageway, passing a stream of hot products of combustion through said passageway and past said coil for heating the mixture passing through the coil to the temperature of conversion, directly passing the mixture thus heated through a second elongated coil of restricted cross sectional area substantially entirely within a second passageway, diverting a portion of the stream of hot products of combustion after said stream has passed the entire length of coil in the first passageway, and passing the remainder of the stream of hot products of combustion through the second passageway and thereby maintaining the mixture in the second coil at the temperature of conversion, the mixture being heated in the first coil to a temperature between 800 and 1000° F., and being maintained in both coils under pressures ranging from 300 to 3500 pounds per square inch.
